UNITED STATES PATENT OFFICE.

ELLIS S. LINCOLN, OF MANSFIELD, OHIO, ASSIGNOR TO THE OHIO BRASS COMPANY, OF MANSFIELD, OHIO, A CORPORATION OF NEW JERSEY.

CURRENT-COLLECTOR SUPPORT.

Application filed October 5, 1921. Serial No. 505,455.

To all whom it may concern:

Be it known that I, ELLIS S. LINCOLN, a citizen of Sweden, residing at Mansfield, in the county of Richland and State of Ohio, ⁵ have invented certain new and useful Improvements in Current-Collector Supports, of which the following is a specification.

My invention relates to a support for current collectors and particularly to that class ¹⁰ of collectors used in the operation of trackless trolley systems where the bus or car is obliged to operate on either side of and to a considerable distance from the overhead conductors as well as in line therewith, and ¹⁵ therefore the support for the collectors must make, at times, a considerable angle with the conductors without disturbing the engagement of the collector therewith. It is also desirable in trackless trolley operation ²⁰ to have a positive and a negative overhead conductor as the wheels of the bus are insulated from the ground by rubber tires and this requires two collectors and in my invention I have provided means of mounting the ²⁵ two collectors on one support. My invention provides for means of yieldably maintaining the distance between the collectors at a predetermined distance apart and also when one collector is moved from its normal ³⁰ position the other collector is moved likewise.

In the accompanying drawing:—

Fig. 1 is a top plan view of my invention. ³⁵ Fig. 2 is a side elevation of my invention. Fig. 3 is a top plan view of a modification of Fig. 1.

In my preferred form shown in Figs. 1 and 2 I provide a pole 1 which may be of any length required and which is upwardly ⁴⁰ spring held by a trolley base secured to the lower end of pole 1 and to the bus roof. I have not shown the base as they are common and well known and I am not bound to the use of any particular design. Adjacent the ⁴⁵ upper end of the pole 1 I secure a head H which is arranged to rotate to a limited degree relative to the pole 1. Secured to the head by means of the clevis members 3—3 are arms 4—4', and to each arm 4—4' is secured the current collecting member C. A bolt or pin 5 holds the clevis to the head. Each clevis swivels relative to the head and the movement is limited by the set screw 6

engaging adjacent parts of the head. The head comprises a sleeve 7 secured to the pole ⁵⁵ 1 by means of a key 8. This sleeve is provided with a flange 9 provided with a slot 10. The head H is also provided with a body 11 which is mounted to rotate on the sleeve but is limited in rotation by the ⁶⁰ tongue 12 projecting into the slot 10 and engaging the sides thereof. The body is held in place on the sleeve by the threaded collar 13.

To the projecting end 14 of the pole 1 is mounted a slideable sleeve 15 and the two adjustable collars 16 and 16' which may be locked in position by the set screws 17. Mounted on the member 14 and between the sleeve and each collar is a spring 18 and 18' ⁶⁵ respectively which yieldingly hold the sleeve in a predetermined position under normal conditions and which position may be altered by changing the position of the collars 16—16' as required. ⁷⁰

To each arm 4—4' is secured a fixed sleeve ⁷⁵ 19, held by screws 20, and extending between each sleeve 19 and the sleeve 15 is a rigid member 21 pivotally secured to the sleeves 19 and 15.

It will be quite evident that if the arm 4 is moved in either direction about the pin 5 that this motion will be transmitted through the bars 21—21 to the arm 4' causing it to move an equal amount and in the same direction with respect to the line of axis of the pole 1. If the stress moving the arm 4 is released and there is no stress holding the arm 4' then the springs 18 and 18' acting on the sleeve 15 will return the arms to their ⁸⁵ normal or predetermined position. By my invention the arms 4—4' are yieldingly maintained with each arm forming the same angle with the axis of the pole 1. ⁹⁰

The modification shown in Fig. 3 is the ⁹⁵ same as the arrangement shown in Figs. 1 and 2 and the construction is quite similar, the exception being the pivoting of the members 21 to the clevis members 3—3.

Having described and shown my invention I claim:—

1. A supporting arm as described, two auxiliary arms pivotally mounted thereon each to receive a current collector and move toward or away from each other in the same ¹⁰⁵ plane about the pivotal point and means

yieldably holding the auxiliary arms in a predetermined position.

2. A supporting arm as described, two auxiliary means pivotally mounted thereon each to support a current collector and to move toward or away from each other about the pivotal point and means yieldably holding the auxiliary means in a predetermined position.

10 3. A supporting arm, two auxiliary members pivotally mounted thereon and each provided with a current collector and forming an angle with the axis of the arm as described and operating to pivot toward or 15 away from each other to change their angular relation and means yieldably holding the auxiliary members in a predetermined position.

4. A support for current collecting means 20 comprising an arm, a pair of inter-connected collector-supporting auxiliary arms movably mounted on said arm to pivot simultaneously toward or away from each other and means yieldably holding the auxiliary means in a predetermined position.

5. The combination with an upwardly movable arm of a plurality of movable arms pivotally mounted on the arm to receive current-collecting devices and forming 30 a changeable angle of divergence with each other and means yieldably holding the movable arms in a predetermined position.

35 6. A support-collecting means comprising an upwardly movable member, means pivotally mounted thereon to receive current-collecting means and to pivot in a transverse direction to the movable member and means yieldably maintaining the pivotally mounted means in a predetermined position.

40 7. A support for current collecting means comprising in combination an upwardly movable member, means pivotally mounted thereon to receive current collecting means and move in a plane, about its pivotal point, 45 common with the axis of the movable member and means yieldably holding the pivotally mounted means in a predetermined position.

50 8. A support for current collecting means comprising an upwardly movable arm, a pair of inter-connected collector supporting arms pivotally mounted thereon and means for yieldably maintaining the pair of arms in a predetermined position.

55 9. A support for current collecting devices comprising a supporting member, a pair of arms operating to change their angular spread mounted on said member to support the collecting devices and yieldable means for maintaining the pair of arms in a predetermined position.

60 10. A support for current collecting devices comprising a supporting member, a pair of arms pivotally mounted on the member and coacting means secured to each arm

to move each arm simultaneously to change the angle formed by each arm with the axis of the member and yieldable means acting on the coacting means to maintain the arms in a predetermined position.

70 11. The combination with a trolley pole, of a pair of inter-connected collector supporting arms movably mounted on said pole to form equal angles with the axis of said pole and to pivot simultaneously to vary 75 said angles uniformly and means yieldably holding the pair of arms in a predetermined position.

12. A support for current collecting devices comprising an upwardly movable member, a pair of arms adapted to receive current collecting devices and mounted to swivel, means interposed between the member and arms to connect the two and means interposed between and connected to the arms to operate the arms in unison about their pivotal point and means yieldably holding the pair of arms in a predetermined position.

80 13. A support for current collecting devices comprising an upwardly movable member, a pair of arms swivelly mounted on the member to move in a common plane and forming angles with the axis of the member and means yieldably holding the arms in a predetermined position.

85 14. A support for current collecting means comprising in combination an upwardly movable member; a plurality of arms each adapted to receive a current collector; means secured to the member and adapted to receive the arms in pivotal relation, means secured to each arm and coacting together to move the arms in unison about their swivel point and resilient means 100 acting upon the last said means to maintain the arms in a predetermined position.

105 15. A support for current collecting devices comprising a trolley pole, a pair of arms operating to change their spread and means interposed between the arms and pole to pivotally secure the arms to the pole and permit the arms to swivel relative to each other to change their spread and resilient means acting upon said interposed means to 110 maintain the arms in a predetermined position.

120 16. A support for current collecting devices comprising a trolley pole, a pair of arms each forming an angle with the axis of the pole and of equal degrees of distention and means coacting with the arms to move them simultaneously, and of equal amount, to vary the angles but maintain them equal and yieldable means acting on said arms 125 to maintain them in a predetermined position.

17. The combination with a trolley pole, of a pair of contact-carrying arms pivotally supported thereby for movement trans-

versely of the pole, and means for normally yieldingly maintaining the arms in a definite spaced relation.

18. The combination with a trolley pole, 5 of a pair of current collectors supported thereby for pivotal movement relatively to one another and transversely of the pole and

means whereby, upon movement of one collector, the other collector is also caused to move, and means for normally maintaining 10 the collectors in definite spaced relation.

In testimony whereof I affix my signature.

ELLIS S. LINCOLN.
